COMBINED HACKSAW BLADE AND HANDLE SUPPORT

Frederick Ehrt, Oley, Pa.

Filed Aug. 18, 1959, Ser. No. 57,218

Term of patent 14 years

(Cl. D93—4)

Fig. 1 is a top plan view of a combined hacksaw blade and handle support showing my new design;

Fig. 2 is an elevational view of one side thereof; and

Fig. 3 is an elevational view of the other side thereof.

The characteristic feature of my design for the article disclosed resides in the handle support member on the end, having the configuration shown.

I claim:

The ornamental design for a combined hacksaw blade and handle support, substantially as shown and described.
